UNITED STATES PATENT OFFICE

LEWIS M. CLEMENT, OF MOUNTAIN LAKES, NEW JERSEY, ASSIGNOR TO F. A. D. ANDREA, INC., OF NEW YORK, N. Y., A CORPORATION OF NEW YORK

LOUD-SPEAKER

Application filed September 11, 1926. Serial No. 134,780.

My invention relates to sound reproducing means, and particularly to such means generally known as loud speakers. My invention relates more specifically to a loud speaker of the sound radiator type as distinguished from the sound box and horn type.

My invention will be better understood by reading the following description in connection with the attached drawings illustrating 10 one embodiment of my invention, and in which:

Fig. 1 is a front elevation of the device;
Fig. 2 is a rear elevation of the device;
Fig. 3 is a vertical section on lines III—III
15 of Figs. 1 and 2;

Fig. 4 is a section on line IV—IV of Fig.
3; and

Fig. 5 is a fragmentary sectional view of
the apex of the sound radiator on a scale
20 larger than that of the other figures.

Referring to the drawings, the device consists of a stand 1 of any desired construction and configuration. The stand illustrated has five supports 2, attached to the stand by 25 screws, or they may be integral with the stand. The stand also has a ring shaped member 3 with two parallel bars 4 and a handle 5.

An actuating unit, later described, is sup-
30 ported by the bars 4.

The supports 2 are provided at their outer ends with threaded openings. A sound radiator 6 is held in place by screws 7 which pass through openings in flexible supporting 35 members 8 which are fastened over openings in the sound radiator board 6 as shown in detail in Fig. 3. The members 8 may be of any suitable material, such as leather. These members are quite flexible in a direction 40 transverse to the plane of the sound radiator, but are relatively inflexible in a direction parallel with the plane of the sound radiator. The screws 7 pass through the members 8 substantially normal to the surface of the 45 sound radiator. As illustrated, the supports 2 are arranged in a circle, but they may be located otherwise than in a circle. In fact I prefer to locate the supports in non-circular 50 positions, as it prevents localized vibrations in the sound radiator. By supporting the

sound radiator at points at differing distances from the apex of the member A, a better reproduction is secured than if the supports were all the same distance from the apex.

The sound radiator consists of two main portions A and B. The portion A is conical in shape and the portion B is frusto-conical. The bases of the portions A and B are fastened together by stitching them together with an edging of tape or braid 9. The manufacture of the sound radiator is facilitated by laying the portion B flat against the portion A while the bases are stitched. They can be moved to the relative positions shown in Fig. 3 after the stitching is completed. The sound radiator may be made of any suitable material, but I prefer fairly heavy paper. The stitching of the sound radiator around the edges adds greatly to its strength and durability. This construction eliminates the cementing heretofore used in devices of this type and which has been a source of weakness thereof.

I also prefer to stiffen the sound radiator 75 so as to avoid localized vibration. In the drawings, I have illustrated two forms of stiffening means. One of these consists of light angle sections 40 spaced around the back face of the cone section A. They pref- 80 erably are located outside the supports 2 and on radial lines passing between the supports 2. In order to obtain maximum stiffness with minimum weight and mass these sections may be provided with one or more ribs, 42. These 85 ribs may run parallel with each other or at any desired angle. The sections may be of any desired size. In addition to the sections 40, I have shown a stiffening ring 41 which covers the area occupied by the supports 2. 90 This ring is also secured by cement to the back face of the cone section A. Other forms of stiffening means may be used if desired. Also the sound radiator gives excellent re- 95 sults without any stiffening means.

The operating unit for the radiator consists of a permanent magnet having ends 10 and 11. Pole pieces 12, 13, 14 and 15 are attached to the ends 10 and 11, respectively, of the magnet and an armature 16 is sup- 100

ported in a mid-position between the pole pieces by a spring 17. The armature 16 is connected to the cone member A by rod 18, member 19 and rod 20, as shown in Fig. 4.

5 The rod 18 has flattened portions 18^a, 18^b near the ends thereof which give flexibility to the rod transversely of its long axis and thus reduces the load on the armature 16. This flexibility is in a plane passing through the 10 rod 18 and the member 19. The rod 20 is connected to the apex of the cone by a clutch device consisting of a screw threaded member 21 (Fig. 5) having gripping members 22 which are forced into holding position by a 15 nut 23 which screws onto the member 21, which in turn is securely fastened to the cone member A by a nut 24 which clamps the material of the cone between the nut 24 and a flange 25 on the member 21. The clutch above 20 described is a very convenient means for connecting the operating rod to the cone. The clutch is easily operated to connect and disconnect the sounding board or sound radiator to and from the operating unit, and at 25 the same time it affords a very firm connection which is not liable to rattle or make other noises. The cone material is reinforced at the apex by the star-shaped metal member 26 on the inside of the cone and the member 27 30 on the outside. The rod 20 has a dampening cover 28 thereon.

The operating unit is supported in position on the stand by two members 29 and 30. These members are fastened to the bars 35 4 of the stand by bolts 31 and 32. The unit is fastened to the members 29 and 30 by bolts 33 and 34. The openings through the ends of members 29 and 30 and through which bolts 31 and 32 pass are elongated so that the 40 position of the unit may be accurately adjusted relative to the opening in the apex of the cone member A.

The base of the frusto-conical member B is free, since it does not touch any part of the 45 supporting mechanism.

Coils 35 surround the armature 16 and wires 36 and 37 connect at one end with the coils 35 and at the other end with the device 50 producing the sound waves to be translated, such as a radio receiver or other device. The coils are connected in such a sense that their reactions are additive.

Other forms of units may be used with my sound radiator, but I prefer the unit 55 illustrated.

The device above described has been successfully used in connection with a radio receiver and produces every faithful reproduction.

60 While I have shown and described one specific embodiment of my invention, I wish it to be understood that my claims are not limited to the specific details shown, as the drawings are merely for the purpose of illustrating one embodiment of the principles 65

of my invention. Many changes may be made in the various details without departing from the spirit of my invention.

I claim:

1. In a loud speaker, the combination of a 70 support, a cone-shaped sound radiator supported at points intermediate its periphery and apex and vibrating means connected to the apex of the cone.

2. In a loud speaker, the combination of a 75 support, a conical sound radiator carried by said support, means for flexibly supporting said sound radiator from said support at points between its periphery and apex and means for imparting vibrations to the apex 80 of said sound radiator to be transformed into sound waves.

3. In a loud speaker, the combination of a 85 flexible sound radiator, means for flexibly supporting said sound radiator at a plurality of points intermediate its periphery and apex and means for imparting vibrations to said sound radiator at the apex.

4. In a loud speaker, the combination of a 90 conical sound radiator, means for flexibly supporting said sound radiator intermediate its periphery and apex and means for imparting vibratory movement at the apex of the cone and along the axis of the cone.

5. In a loud speaker, the combination of a 95 sound radiator in the form of a shallow cone, means for flexibly supporting the sound radiator between the base and apex so as to leave the base free and means connected to the apex of the cone for imparting vibrations thereto.

6. In a loud speaker, the combination of a 100 conical sound radiator, a plurality of radial openings in said sound radiator, flexible members over said openings and means supporting said sound radiator through said 105 flexible members.

7. In a loud speaker, the combination of a support, a cone-shaped sound radiator supported at points intermediate its periphery and apex, a frusto-conical member attached 110 to the periphery of said sound radiator, and vibrating means connected to the apex of the cone.

8. In a loud speaker, the combination of a support, a conical sound radiator carried by 115 said support, means for flexibly supporting said sound radiator from said support at points between its periphery and apex, a frusto-conical member attached to the periphery of said sound radiator, and means for imparting vibrations to the apex of said sound radiator to be transformed into sound waves.

9. In a loud speaker, the combination of a support, a conical sound radiator carried by 120 said support, means for flexibly supporting said sound radiator from said support at points between its periphery and apex, an open ended frusto-conical member attached to the periphery of said sound radiator, and means for imparting vibrations to the apex 125 130

of said sound radiator to be transformed into sound waves.

10. In a loud speaker, the combination of a conical sound radiator, a plurality of radial openings in said sound radiator, flexible members over said openings, means supporting said sound radiator through said flexible members, and a frusto-conical member attached to the periphery of said radiator.
11. In a loud speaker, the combination of a conical sound radiator, a plurality of radial openings in said sound radiator, flexible members over said openings, means supporting said sound radiator through said flexible members, and a frusto-conical member attached to the periphery of said radiator and extending in an opposite direction and wholly supported by said radiator.

LEWIS M. CLEMENT.
